United States Patent

Des. 242,267

Patented Nov. 9, 1976

242,267

ORIENTAL TERRACED GARDEN SPROUTER

Edward J. Feeney, Jr., 1047 Tenby Road,
Bryn Mawr, Pa. 19312

Filed Mar. 17, 1975, Ser. No. 558,897

Term of patent 14 years

Int. Cl. D11—02

U.S. Cl. D11—155

Fig. 2

FIG. 1 is a top front perspective of an oriental terraced garden sprouter showing my new design;

FIG. 2 is an exploded view, shown for clarity of illustration; and

FIG. 3 is a top perspective of the sprouting tray and the barrier member removed for clarity of illustration.

I claim:

The ornamental design for an oriental terraced garden sprouter, as shown and described.
